VENDING MACHINE

Boynton Eldredge, Seattle, Wash.

Application February 14, 1938, Serial No. 190,448

8 Claims. (Cl. 194—57)

This invention relates to improvements in coin-controlled vending machines. Its general object is to simplify the parts used, to provide an especially durable and easily operated unit, and to form a machine which is proof against tampering.

My invention is further aimed toward the provision of a coin control for the vending mechanism permitting introduction of multiple coins to a receiving chute and subsequent repetitive ejection of the vendable merchandise by use of the coins successively; toward the provision of a coin-released vending structure using a locking lever which normally is disposed in a releasing position and which moves into a locking position only upon failure to insert a coin when attempting a vending action, thereby obviating use of the coin's weight, an objectionable characteristic of many coin-controlled vending machines, to depress the locking lever into its releasing position; and toward the provision of numerous other advantages in construction and operation which will appear in the course of the following description and claims.

The invention consists in the novel construction, and in the adaptation and combination of parts hereinafter described and claimed.

In the drawings:

Figure 1 is a fragmentary side elevational view of a vending machine constructed according to the present invention, the near wall being broken away to obtain a full-line showing of the coin-control chamber.

Fig. 2 is a horizontal section thereof taken on the line 2—2 of Fig. 1.

Fig. 3 is a transverse vertical section on the line 3—3 of Fig. 2.

Fig. 4 is a fragmentary transverse vertical section on the line 4—4 of Fig. 1.

Fig. 5 is an enlarged detail longitudinal vertical section taken through the coin-control chamber and indicating the parts in position preparatory to initiating a vending movement of the commodity drawer; and

Fig. 6 is a view similar to Fig. 5 excepting that the parts are shown in the slightly advanced locking position assumed upon a fraudulent attempt to vend merchandise.

The machine comprises a casing 8 providing a hopper 9 of any suitable size or shape for the merchandise to be vended, as for example a bulk commodity such as peanuts, the hopper having a discharge opening leading to a measuring pocket 10 carried by a commodity-vending drawer 11 which is slidably mounted in a chamber formed

by side walls 12 and 13 and by bottom and top walls 14 and 15 of which the latter is or may be the floor of the hopper. For limiting the travel of the drawer a shaft 16 extends transversely thereof with one or both ends projected through slots 17 provided in the side walls. A spring 18 operates to return the drawer to its closed position, this spring connecting at its forward end with the drawer and at its rear end hooking over a crank portion 20' formed on a transverse shaft 20, the shaft being received in open slots 21 provided in the side walls.

Said side wall 12 is disposed in spaced relation to the exterior wall 8' of the casing and in the space therebetween I provide two chambers, an inner coin-control chamber into which an end 16' of the shaft 16 extends and an outer chamber separated therefrom by a partition 22. Received in the coin-control chamber is a vertically disposed latching plate 23 which finds a pivotal mounting on said protruding shaft end 16' and is movable thereby longitudinally of the chamber simultaneously with the longitudinal movement of the drawer, the plate having upturned bearing lugs 24, 25 and 26 which ride over the partition 22 and downturned bearing lugs 27, 28, 29 and 30 which ride over the wall 12. Through the provision of these lugs the plate lies approximately centrally as regards the coin-control chamber and forms a coin-receiving chest between the plate and the partition, such chest being open at the top and defined at one side by the upturned lug 24, at the opposite side by an expressed finger 31, and at the bottom by a downwardly inclined shear finger 32. The top opening in the normal retracted position of the drawer lies immediately below a coin chute 33.

Describing said latching plate in more particularity, the same is rocked in one direction about its pivotal axis under the influence of a rocker arm 20" formed as an extension of the shaft 20 and is rocked in the opposite direction by a sear spring 34, the rocker arm tending to depress the front or toe portion 23' of the plate under the influence of the major spring 18 whereas the opposingly disposed sear spring, a minor spring, acts to elevate this toe portion. The influence of the major spring is applied through the upturned lug 25 and depresses the toe portion of the plate to a position at which the upper edge of a coin introduced to the chest clears the ceiling of the control chamber, a positioning which is obtained by contact of the rear or heel portion 23" of the plate against a rear prolongation of the ceiling.

It is hereby pointed out, in the arrangement of spring 18, that the contractive influence thereof is applied through shaft 16 to retract the plate and in opposition thereto through crank 20' to rock the plate in its toe-depressing movement, an arrangement which operates by the lever differential therein obtaining to rock the arm 20'' rearwardly upon spring retraction of the drawer and thereby position the arm to the rear of the coin chute as illustrated in Fig. 5 from whence forward rocking movement of the arm positions the arm below the mouth of the chute to prevent discharge of coins therefrom as the drawer is moved forwardly (Fig. 6).

18 The sear spring 34 is received over the shaft end 16' between plate 23 and the wall 12 and its two ends engage the downturned lug 27 and the underside of the wall 14, such latter end tracking this wall as the drawer moves forward into its vending position. The action of the sear spring, as stated, is to elevate the toe portion of the latching plate and this action is obtained following travel of the plate forwardly into a position at which rocker arm 20'' is brought into contact with a diagonal stop shoulder 22' of the partition 22. This elevating movement, however, is normally opposed by the engagement of a coin against the ceiling of the control chamber, which said ceiling functions as a track along which the upper edge of the coin slides, and is effective only upon an attempt to fraudulently vend the commodity from the hopper without using a coin, whereupon the toe 23', is caused to lodge in a ceiling detent 35. Spaced forwardly from this detent is a second detent 36 which complements the former detent and acts in response to lateral ejection of the coin through an opening 37 to prevent fraudulent vending through the operation of returning the drawer for only a slight distance, namely a return movement which is insufficient to pass the toe beyond the detent 35 yet sufficient to have the rear edge of the measuring pocket clear the forward edge of the hopper mouth.

45 Tracing the operation to clarify the same it is seen that any number of coins can be introduced to the chute and that only one of these coins will be used in each successive vending operation. The normal position of the latching plate when fully retracted locates the coin chest immediately below the chute and in this position the rocker arm 20'' is moved rearwardly to clear the mouth of the chute while its resistant influence depresses the toe 23'. The coin within the coin chest tracks its upper edge against the ceiling of the chamber following movement of the plate forwardly to a point at which the rocker arm rests against the stop shoulder 22', the coin depressing the toe portion of the plate by the engagement of its lower edge against the shear finger 32. As the coin passes the rear lip of the opening 37 the sear spring by its elevation of the shear finger 32 forces the lower edge of the coin laterally through the opening in the manner shown by dotted lines in Fig. 4. In the return movement of the plate the toe 23' rides freely over the detents 35-36 and the plate, upon contact as between the lug 25 and the rocker arm, is depressed into its coin-receiving position.

70 The structural arrangement and design of the several parts of my advanced coin-control for vending machines is believed clear and while I have illustrated and described a preferred embodiment thereof it is my intention that no limitations be read into the hereto annexed

claims excepting as the same are necessarily introduced thereto, and that the language as used therein be given a scope in its interpretation commensurate with the degree to which the art is advanced.

5 What I claim is:

1. Control mechanism for a coin-released vending machine employing a spring-retracted transfer member movable in reciprocatory travel, said mechanism comprising the combination of the 10 spring by which said transfer member is retracted, a latching plate movable in reciprocatory travel with said transfer member and supported for independent pivotal movement, said latching plate providing a coin chamber, a coin chute located to register with the coin chamber in the retracted position of the plate, means operated by said spring in the retracted position of the latching plate for rocking the latching plate in one direction of its pivotal movement, means by which a coin in the coin chamber maintains the latching plate in its spring-rocked position during forward travel of the latching plate, a spring restrained by the plate-rocking means in the retracted position of the latching plate and, in the absence of a coin within the coin chamber, acting in response to forward travel of the latching plate to rock the plate in the other direction of its pivotal movement, and a catch positioned such as to be engaged by the plate in response to said last-named rocking movement of the plate for locking the plate against forward movement.

2. The structure defined in claim 1 wherein the spring-operated means by which the plate is rocked in the first-named pivotal movement comprises a rocking arm engageable with the plate and movable from a normal position interrupting the discharge of coins from the coin chute into a position permitting free delivery of a coin to the coin chamber.

3. Control mechanism for a coin-released vending machine employing a manually-withdrawn and spring-retracted sliding drawer for the commodity to be vended, said mechanism comprising the combination of the spring for retracting the drawer, a latching plate supported for independent pivotal and collective sliding movement with the drawer and formed to provide a coin chamber operating to expose the upper edge of a coin received therein, a coin chute located to register with the coin chamber in the retracted position of the plate, a rocker arm operated by the spring and engaging the plate only in the retracted position thereof to depress the plate about its pivotal axis into a position permitting free admission of the coin from the chute into the coin chamber, a track engaged in the forward travel of the plate by the exposed edge of the introduced coin to maintain the plate in said depressed position, a minor spring restrained by the rocker arm in the retracted position of the plate by reason of the greater influence of said first-named spring and, in the absence of a coin within the coin chamber, operating in response to forward travel of the plate to elevate the plate about its pivotal axis, and a catch positioned such as to be engaged by the plate in response to said elevation of the latter for locking the plate against forward movement.

4. Control mechanism for a vending machine formed with a slide chamber defined at one side by a longitudinally-slotted wall, said machine having a shaft extending through said slot into the slide chamber and operatively connected with the vending structure of the machine to obtain

reciprocatory movement of the shaft from one to the other extreme of the slot, said mechanism comprising the combination, including the slide chamber, its slotted wall, and the shaft, of a latching plate received in the slide chamber and supported by the protruding end of the shaft for sliding movement longitudinally of the slot and pivotal movement about the shaft as an axis, said latching plate being formed to provide a coin-receiving chamber, a coin chute located to register with the coin chamber in one extreme of the plate's longitudinal movement, a spring of major spring characteristic and means influenced thereby and engaging the plate to depress the plate about the axis of the supporting shaft in the chute-registering position of the plate, a track engaged in the travel of the plate directly from its chute-registering position, by a coin in the coin chamber to maintain the plate in its spring-depressed position, a spring of minor spring characteristic acting on the plate and effective in the absence of a coin within the coin chamber and in the travel of the plate directly from its chute-registering position to elevate the plate about the supporting shaft as an axis, and a catch positioned such as to be engaged by the plate in response to said spring-operated elevational movement of the plate for locking the plate against movement directly from the chute-registering position thereof beyond a predetermined point short of the full stroke of the plate.

5. In a coin-controlled vending machine, in combination, a coin-released latching plate pivotally mounted on a longitudinally movable axis and formed to provide a coin chamber, a coin chute located to register with the coin chamber at one extreme of the plate's longitudinal movement, a rocker arm engaged by the latching plate in said registering position and movable thereby from a position operative to interrupt discharge of coins from the coin chute into a position permitting free delivery of a coin to the coin chamber, a spring operating in the absence of a coin within the coin chamber to rock the plate in one direction of its pivotal movement, and a catch,

positioned such as to be engaged by said plate only in response to pivotal movement of the latter by the action of said spring, for locking the plate to prevent movement thereof to the opposite extreme of its longitudinal movement.

6. In a locking device for a vending machine, in combination, a coin-released latching plate supported for reciprocatory movement and formed to provide a coin chamber, a coin chute located to register with the coin chamber in one extreme of its reciprocatory movement, and a rocker arm normally located to interrupt discharge of a coin from the coin chute and movable by engagement with the latching plate in said chute-registering extreme of the plate's movement into a position permitting free delivery of a coin from the chute into the coin chamber.

7. In a locking device for a vending machine, the combination of a coin-released latching plate pivotally mounted on a longitudinally movable axis and having a coin chamber operating to expose the edge of a coin received therein, a coin chute located to register with the coin chamber in one extreme of its longitudinal movement, a spring influencing the latching plate to rock the same in one direction of its pivotal movement, a catch operating to engage said plate in response to said spring-influenced pivotal movement to lock the plate against travel from its coin-registering to the opposite extreme of its longitudinal movement, and a track operating, in the travel of the plate from its coin-registering position to engage the exposed edge of a coin received in the coin chamber for resisting said spring-influenced pivotal movement of the plate.

8. The structure defined in claim 7 wherein means are provided to discharge the coin from the coin chamber following travel of the plate past the catch but prior to the machine's vending action, and a complementary catch arranged to operate following said coin ejection as a means to prevent a second forward movement of the plate upon a partial return thereof insufficient to bring the plate into operative engagement with the first-named catch.

BOYNTON ELDREDGE.
